UNITED STATES PATENT OFFICE.

MORRIS WINNING, OF OTTAWA, ONTARIO, CANADA.

SWITCH.

1,267,950.

Specification of Letters Patent. Patented May 28, 1918.

Application filed May 3, 1917. Serial No. 166,250.

To all whom it may concern:

Be it known that I, MORRIS WINNING, a subject of the King of Great Britain, and a resident of the city of Ottawa, in the Province of Ontario and the Dominion of Canada, have invented certain new and useful Improvements in Switches, of which the following is a full description.

This invention relates to improvements in switches particularly adapted for use on street railways, narrow gage tracks and on railroads generally, and the objects of the invention are to permit of the switch being set by the approaching car or train, so that the desired path of travel may be taken without the necessity of manually setting the switch, to render the switch operating device water tight, so that it will not deteriorate owing to exposure to the elements, to simplify the arrangement of the several parts and generally to adapt the same to better perform the functions required of them.

With these and other objects in view, the invention consists essentially of the improved construction particularly described and set forth in the following specification and accompanying drawings forming part of the same.

In the drawings,

30 Figure 1 is a fragmentary plan view of a railroad embodying the present invention.

Fig. 2 is a sectional elevation of the road showing car mechanism designed to coact with the track mechanism.

35 Fig. 3 is a fragmentary plan view of the track showing the depression with which the car operating device coacts in operating the switch.

Fig. 4 is a sectional elevation of the track showing the car mechanism in position for operating the track mechanism.

Fig. 5 is a perspective view of an alternative form of switch operating mechanism.

Fig. 6 is an end elevation of the same.

45 Like characters of reference refer to like parts in the several figures.

Referring to the drawings, A represents a railroad of any usual description consisting of the main track B and the side track C which is controlled by the switch operating mechanism D. This switch operating mechanism consists of a pair of boxes or casings 10 and 11 operatively connected by a pipe 12, so that the said casings and pipe will contain the working mechanism and protect the same from moisture, dirt and the like.

A crank shaft 13 extends through the pipe 12 with the crank end located in the casing 10 and rotatably supported by the brackets or bearings 14, the end of the shaft extending into the casing 11, being provided with a beveled gear 15. The beveled gear 15 meshes with the beveled gear 16 carried by the vertically disposed shaft 17 on the upper end of which a star wheel 18 is rigidly mounted.

This star wheel is protected by a cover or plate 19 which extends partially above the same only permitting one arm of the star wheel to project beyond the edges of the same, so that it may engage with the car mechanism E in a manner to be made clear hereafter.

The crank end of the shaft 13 is pivotally connected to the rod 20, while the switch 21 is pivotally connected to the rod 22, and the free ends of the rods 20 and 22 lie alongside of each other and are embraced by the spiral spring 23 which is connected to the free end of the said rods in such a manner that while it permits of the switch 21 being opened on rotation of the crank shaft 13, will at the same time give the desired yield to prevent breakage taking place should the switch 21 be fouled with stones, dirt or the like.

The car mechanism E consists of a plunger 24 having a roller 25 on the lower end thereof, the said plunger being operatively mounted on the foot board of the car F, and being spring controlled by means of the spiral spring 26.

The upper end of the plunger 24 is provided with a foot pad 27, so that it may be readily depressed by the driver, and on pressure being removed from the foot pad 27, the plunger 24 will immediately return to its normal elevated position as shown in Fig. 2.

The roller 25 will coact with the depression 28 between the tracks adjacent to the star wheel 18 and by the use of this roller any undue friction between the plunger and depression is eliminated.

In that form of the invention illustrated in Figs. 5 and 6, the crank shaft 13 coacts with a locking member 30 which consists of a pair of resilient plates 31 adapted to engage with the shaft on each side of the crank portion, the plates 31 being operatively supported by the bracket 32.

It will be seen that the pairs of plates 31,

while being located on opposite sides of the crank portion provide a space 33 therebetween through which the rods 20 and 22 operate. In other respects the switch is 5 the facsimile of that already described and need not further be enlarged upon.

When a railroad is equipped with a device of this nature and the car F is approaching a switch, it is only necessary for 10 the driver to depress the plunger 24 causing the same to co-act with the star wheel 18, which will thus be rotated through one step of a revolution thereby rotating the crank shaft 13 and transmitting the motion to the 15 switch 21.

Should, for instance, the driver desire to continue on the main track B, the plunger 24 on contacting with the star wheel 18 will 20 rotate the crank shaft, so that the switch 21 is opened, permitting the car to continue 25 in the desired path of travel.

Should a following car, however, desire then to take the side track C, the driver depresses the plunger 24 to engage the star 25 wheel 18 and in this manner rotate the crank shaft 13 to close the switch 21 and thus permit of the car taking the side track C.

When that type of the invention illustrated in Figs. 5 and 6 is installed in a rail- 30 road, it will be seen that there is no possibility of the crank shaft 13 becoming acci-

dently rotated, as it requires a decided force to rotate the same, due to the said crank shaft being held between the resilient plates 31 of the locking member. In this 35 manner the switch mechanism cannot be interfered with by any unauthorized person in any way and the device is always in an operative position.

As many changes could be made in the 40 above description and many apparently widely different embodiments of my invention within the scope of the claims constructed without departing from the spirit or scope thereof, it is intended that all matter 45 contained in the accompanying specification and drawings shall be interpreted as illustrative and not in a limited sense.

What I claim as my invention is:

The combination with a railway track, of 50 track switching means comprising a crank shaft, spring including means operatively connecting the crank shaft to the switch, and means coacting with the crank shaft, comprising yoke-shaped resilient members 55 on each side of the spring including means.

In witness whereof I have hereunto set my hand in the presence of a witness.

MORRIS WINNING.

Witness:

RUSSEL S. SMART.
